UNITED STATES PATENT OFFICE.

ARTHUR SHELLEY KING, OF NEW HAMPTON, MISSOURI.

MEANS FOR PROTECTING TIMER WIRES.

Specification of Letters Patent.

Patented Oct. 8, 1918.

1,281,172.

Application filed September 11, 1916, Serial No. 119,529. Renewed March 23, 1918. Serial No. 224,390.

To all whom it may concern:

Be it known that I, ARTHUR S. KING, a citizen of the United States, residing at New Hampton, in the county of Harrison and State of Missouri, have invented certain new and useful Improvements in Means for Protecting Timer-Wires; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in protecting devices for timer wires on engines and especially adapted for the type commonly used upon Ford cars.

The invention consists of a simple and efficient device of this nature so arranged as to protect the timer and wires from short circuiting, due to accumulation of oil, liquids, etc.

My invention comprises a protecting device having various details of construction, combinations and arrangements of parts which will be hereinafter fully described, shown in the accompanying drawings and then specifically defined in the appended claim.

I illustrate my invention in the accompanying drawings, in which:—

Fig. 1 is a side elevation of my invention shown as applied to the timing device.

Fig. 2 is a sectional view through the casing.

Fig. 3 is a vertical sectional view on line 3—3 of Fig. 1.

Reference now being had to the details of the drawings by letter, A designates an oscillating timer gear case having an integral handle B to which the controlling rod B'

is pivotally connected. C, D, E and F designate terminals to which the timing wires H are respectively connected.

The casing is designated by letter L and is of general cylindrical shape with a conical portion K, slotted as at T to receive the swinging arm B of the timer device, said casing also having a groove B² through which a fan belt, not shown, may pass. A tubular projection N of the casing is adapted to receive the timing wires and serving as a means to thoroughly protect the same from oils, liquid or other foreign matter.

A suitable insulating lining, designated by letter S, is placed within the cover and serves to prevent the metal casing from short circuiting the timer connecting posts.

While I have shown a particular shape of construction of protecting device as applied to the usual timing mechanism employed in a certain type of automobile, it will be understood that the shape of the timer and arrangement of the same may be varied to adapt the same for use in connection with other forms of timing apparatus.

What I claim to be new is:—

In combination with a timer protecting shell of cylindrical form with a conical shaped face having at its apex an indenture and provided with an arm, a casing in which the shell is mounted and provided with a conical projection, having a beading adapted to engage said indenture, the inclined wall of the shell being provided with an elongated slot to receive an arm of said shell, a portion of the case being extended to form a passageway to protect timer wires.

In testimony whereof I hereunto affix my signature in presence of two witnesses.

ARTHUR SHELLEY KING.
